(57) **CLAIM**

The ornamental design for an adapter handle, as shown and described.

DESCRIPTION

FIG. 1 is a first perspective view of an adapter handle. FIG. 2 is a second perspective view of the adapter handle of FIG. 1.

FIG. 3 is a top plan view of the adapter handle of FIG. 1. FIG. 4 is a bottom plan view opposite of the adapter handle of FIG. 3.

FIG. 5 is a first elevational view of the adapter handle of FIG. 1.

FIG. 6 is a second elevational view rotated 180 degrees of the first elevational view of the adapter handle of FIG. 5.

FIG. 7 is a third elevational view of the adapter handle rotated 90 degrees relative to the first elevational view of FIG. 1; and,

FIG. 8 is a fourth elevational view rotated 180 degrees relative to the third elevational view of FIG. 7.

The broken lines illustrate environmental supplementary structure of the adapter handle, and form no part of the claimed design.
